CLAIM

The ornamental design for a combined cutting board and seat, as shown and described.

DESCRIPTION

FIG. 1 is a front perspective view of a combined cutting board and seat showing our new design;

FIG. 2 is a top plan view of our combined cutting board and seat showing our new design;

FIG. 3 is a bottom plan view thereof;

FIG. 4 is a front-edge elevational view thereof;

FIG. 5 is a rear-edge elevational view thereof; and,

FIG. 6 is a right side elevational view thereof.

The knife and bucket, fragmentarily depicted, have been shown for illustrative purposes only.

FIG. 1.

FIG. 2.

*FIG. 3.**FIG. 4.**FIG. 5.**FIG. 6.*
